DESCRIPTION

FIG. 1 is a front perspective view of a tip for a ground engaging machine implement showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

CLAIM

The ornamental design for a tip for a ground engaging machine implement, as shown and described.

FIG. 8 is a front perspective view of a second embodiment thereof;
FIG. 9 is a front view thereof;
FIG. 10 is a rear view thereof;
FIG. 11 is a left side view thereof;
FIG. 12 is a right side view thereof;
FIG. 13 is a top view thereof;
FIG. 14 is a bottom view thereof;
FIG. 15 is a front perspective view of a third embodiment thereof;
FIG. 16 is a front view thereof;
FIG. 17 is a rear view thereof;
FIG. 18 is a left side view thereof;
FIG. 19 is a right side view thereof;
FIG. 20 is a top view thereof;
FIG. 21 is a bottom view thereof;
FIG. 22 is a front perspective view of a fourth embodiment thereof;
FIG. 23 is a front view thereof;
FIG. 24 is a rear view thereof;
FIG. 25 is a left side view thereof;
FIG. 26 is a right side view thereof;
FIG. 27 is a top view thereof;

FIG. 28 is a bottom view thereof;
FIG. 29 is a front perspective view of a fifth embodiment thereof;
FIG. 30 is a front view thereof;
FIG. 31 is a rear view thereof;
FIG. 32 is a left side view thereof;
FIG. 33 is a right side view thereof;
FIG. 34 is a top view thereof;
FIG. 35 is a bottom view thereof;
FIG. 36 is a front perspective view of a sixth embodiment thereof;
FIG. 37 is a front view thereof;
FIG. 38 is a rear view thereof;
FIG. 39 is a left side view thereof;
FIG. 40 is a right side view thereof;
FIG. 41 is a top view thereof; and,
FIG. 42 is a bottom view thereof.

The dashed broken lines represent structure or features which form no part of the claimed design; the broken lines themselves form no part of the claimed design.

The line shading in FIGS. 1-42 represents contour.
